UNITED STATES PATENT OFFICE.

LOUIS P. VALIQUET, OF NEWARK, NEW JERSEY, ASSIGNOR TO COMPLEX AURAL COMPANY, OF NEWARK, NEW JERSEY, A CORPORATION OF NEW JERSEY.

DESIGN FOR A SOUNDING-BOARD FOR TALKING-MACHINES.

No. 40,130.

Specification for Design.

Patented July 6, 1909.

Application filed May 8, 1909. Serial No. 494,944. Term of patent 7 years.

To all whom it may concern:

Be it known that I, LOUIS P. VALIQUET, a citizen of the United States of America, residing at Newark, county of Essex, State of New Jersey, have invented a new, original, and ornamental Design for Sounding-Boards for Talking-Machines, of which the following is a specification, reference being had to the accompanying drawing, forming part thereof.

The figure is a front elevation of a sounding board and frame therefor showing my design.

1 represents the sounding board proper, 2 the outer frame, and 3 the inner frame having openings 4, 4.

I claim:

The ornamental design for a sounding board for talking machines as shown and described.

LOUIS P. VALIQUET.
